Philip K. Duran, Jr.

UNITED STATES PATENT OFFICE.

ALBERT H. MORTON, OF LOWELL, MASSACHUSETTS.

CARDING-ENGINE.

1,161,067.

Specification of Letters Patent. Patented Nov. 23, 1915.

Application filed July 22, 1915. Serial No. 41,315.

To all whom it may concern:

Be it known that I, ALBERT H. MORTON, a citizen of the United States, residing at Lowell, in the county of Middlesex and State of Massachusetts, have invented certain new and useful Improvements in Carding-Engines; and I do hereby declare the following to be a full, clear, and exact description of the invention, such as will enable others skilled in the art to which it applies to make and use the same.

The present invention relates to an improvement in carding engines.

The improvement in carding engines, illustrated and described in my co-pending application, Serial No. 7,923, contemplated specifically the application of the driving power to the top flats within the periphery of the top flat disks and at the top only of the disks so as to cause the top flats to be held in contact with the surface of the disk in their progress by the stripping plate and the stripping comb.

As therein shown, the top flat disks are mounted to turn independently upon bearings which are eccentric to the shaft upon which the top flat driving sprockets are secured, so that the sprockets engage and drive the top flat chains near the tops of the disks above the stripping comb. The construction therein illustrated, however, was only adapted for new work.

It is the object of the present invention to provide a construction and arrangement of parts which is especially adapted for incorporation in existing machines, and which will enable the above improvement to be readily and conveniently applied to such machines at a minimum expense, and without change in the top flat chains or in the positions of the sprocket shaft and stripping comb or in the driving connections for the shaft and comb.

To these ends the invention consists in the features of construction and combinations and arrangements of parts hereinafter described and particularly defined in the claims.

In the accompanying drawing illustrating the preferred form of the invention, Figure 1 shows a portion of the main cylinder, the top flats, the top flat chain sprocket and associated parts, and Fig. 2 is a vertical section of a part of the bracket, the eccentric, the disk, and the sprocket.

The illustrated embodiment of the inven-

tion is described as follows: The main cylinder 5 is provided with the usual card clothing 6. The dash and dotted line 7 designates the surface of the bend upon which the top flats 8 travel, and by which they are maintained in proper relation to the main cylinder, so that the clothing 9 of the top flats is properly presented to the clothing of the main cylinder. The traveling flats 8 are articulated in the usual manner with the top flat chain 10, which flats are driven by the sprocket wheel 11 mounted upon the sprocket wheel shaft 12 and held against relative movement thereto by the key 13. The top flat disk 14 is rotatably mounted between the bracket 15 and the sprocket 11 upon an eccentric 16 supported upon the sprocket wheel shaft, and held from rotation by the pin 17 by which the eccentric is secured to the bracket 15. The eccentric 16 is provided with a shoulder or flange 18 which engages one side of the hub of the top flat disk. The other side of the hub of the top flat disk engages the hub of the sprocket wheel 11. These two parts, therefore, maintain the top flat disk from the endwise movement on the sprocket wheel shaft. It will be observed that the top flat disk 14 supports and moves with the top flats, and at a different rate of surface speed from that of the pitch line of the top flat sprocket 11. The only changes necessary to be made in the carding engine for the purpose of adapting the use of this invention thereto is to drill a hole in the bracket 15 to receive the pin 17, to apply the new parts—the sprockets, eccentrics and the disks. This makes, therefore, a very inexpensive construction for changing over existing machines to embody the invention of the said application.

Since in changing over existing machines the old top flat chains are retained, the pitch of the new sprocket 11 will be determined by the pitch of these chains, while its diameter must be such that its lower portion will clear the lugs on the flats. The eccentric 16 is so constructed and arranged that its center is in, or substantially in, a line bisecting the angle between a line passing through the centers of the sprocket shaft and main cylinder and a line passing through the center of the sprocket shaft and the point of operation of the stripping comb. This construction and arrangement of the eccentric enables the disk to be so pro-

portioned that the position of its surface at the line passing through the centers of the cylinder and sprocket, and at the point of operation of the stripping comb, will practically coincide with the position of the surface of the old disk at these points, so that the top flats will be accurately positioned to coöperate with the main cylinder at the point where the flats leave the cylinder, and 10 to coöperate with the old stripping comb. The disk is made of such a size that its surface will coincide with the surface of the old disk at the points above referred to, and will also so support the top flats that the pitch 15 line of the lugs on the flats will properly coincide with the pitch line of the sprocket at that portion of the disk surface which coincides with the driving portion of the sprocket. With the disk thus proportioned 20 and mounted upon an eccentric constructed and arranged as described, the surface of the top flats will not only be in practically the same position at the points referred to as when supported upon the old disk, but 25 will also be traveling in practically the same directions at these points, and thus the proper coöperation of the old top flats with the old main cylinder and stripping comb when operated by the improved driving 30 mechanism will be insured.

In modifying existing machines only one of the two sprockets need be provided with the adjusting means illustrated in the drawing, the other being integral and splined 35 to the shaft in the same manner at the opposite end of the sprocket wheel shaft.

Having thus described the invention, what is claimed is:

1. A carding engine, having, in combination, a main cylinder, revolving top flats, a top flat sprocket and shaft, a disk for supporting the top flats, a bracket, an eccentric pinned to the bracket and affording a support for the top flat disk eccentric to the 45 top flat sprocket shaft.

2. An eccentric for use in reconstructing

carding engines provided with a hole to receive the pin by which the eccentric is pinned fast to the bracket, and an eccentric surface to receive the top flat disk. 50

3. An eccentric for use in reconstructing carding engines provided with a hole to receive the pin by which the eccentric is pinned fast to the bracket, an eccentric surface to receive the top flat disk, and a shoulder encircling the eccentric and affording 55 an end bearing for one side of the top flat disk.

4. An eccentric and to flat disk, the eccentric being provided with an eccentric hole to receive the sprocket wheel shaft of the carding engine, and a surface to receive the top flat disk, combined with a device for securing the eccentric to the bracket of a carding engine. 60

5. Mechanism for reconstructing top flat drives of carding engines having top flat supporting disks and top flat sprockets, comprising top flat driving sprockets adapted to be secured to the sprocket shaft of the machine, and of a size to engage the top flats near the top only of the top flat disks, top flat disks and eccentric bearings for the top flat disks constructed to support the disks with their surfaces at the point where the top flats leave the main cylinder and at the point of operation of the stripping comb substantially coincident with the positions of the surfaces of the old disks at these points. 70

6. A carding engine, having, in combination, a main cylinder, a stripping comb, revolving top flats, a disk for supporting the top flats, a sprocket for driving the top flats, and an eccentric bearing for the disk 85 having its center substantially midway between a line passing through the centers of the sprocket and main cylinder and a line passing through the center of the sprocket and the point of operation of the stripping 90 comb.

ALBERT H. MORTON.
